UNITED STATES PATENT OFFICE.

EDWARD M. KEMP, OF RHEINELANDER, WISCONSIN.

DESIGN FOR A SCREEN-DOOR.

SPECIFICATION forming part of Design No. 23,338, dated June 5, 1894.

Application filed April 27, 1894. Serial No. 509,276. Term of patent 7 years.

To all whom it may concern:

Be it known that I, EDWARD M. KEMP, a citizen of the United States, residing at Rhinelander, in the county of Oneida and State of Wisconsin, have invented a certain new and original Design for Screen-Doors; and I do hereby declare the following to be a full, clear, and exact description of the invention, such as will enable others skilled in the art to which it appertains to make and use the same.

The accompanying drawing represents a front elevation of a screen-door showing my design. The leading features of the latter are, first a series of upright parallel parts having the appearance of slender molded posts or rods between two transverse bars; second, a pair of crossed parts having the appearance of bars rounded and decorated, arranged in the form of a St. Andrew's cross and bisecting through each diameter a rectangular space bordered by framework having inwardly projecting decorated knobs or cones; third the background of reticulated screen surface against which they stand.

A represents the exterior elongated rectangular upright frame of the door, B the screen inclosed therein, C, a horizontal bar extending across the screen from side to side of the frame near the middle, E a bar similar thereto and arranged parallel therewith below it, F a series of slender upright grooved and molded rods or posts connecting these bars and G a pair of long rods or rounded bars arranged in the form of a St. Andrew's cross, bisecting through both diameters, and dividing into four V-shaped spaces the square space formed by bar E and the bottom and lower part of the sides of the frame. From the middle of each of the four sides of this square space a decorative cone or pointed knob H, having a bead or collar h around it, projects into the said space. At the point of crossing of the bars G an annular bead or raised or-

namental ring g is formed and the parts of the said bars next it as shown at g' have a flattened appearance, fluted, ridged or grooved in parallel lines, so that the central part of the St. Andrew's cross appears approximately like a star having four broad rays. From this, four arms diverge to the corner of the square, each consisting of one end of one of the crossed bars G and having a rounded molded tapering form like that of some table legs.

A black border D surrounds the upper part of the screen within the frame above the bar C. Black lines d between the ends of the crossed bars G and decorative cones or knobs H make a broken border of similar nature about the lower square of the screen. These black borders set off more distinctly the pleasing contours of the design. The reticulated surface of the screen forms an attractive background. The crossed rods in their ornamented square combine artistically with the horizontal bars and intervening series of small upright molded posts above them, yet each of these two leading features has a distinct value as part of a design.

In describing the said design, I do not wish to be understood as claiming the material, nor any mechanically useful part as such; but merely as employing terms intended to convey to the mind of the reader clearly, fully and minutely the distinguishing features of the decorative design itself.

Having thus described my invention, what I claim as new, and desire to secure by design Letters Patent, is—

The design for a screen-door herein shown and described.

In testimony whereof I affix my signature in presence of two witnesses.

EDWARD M. KEMP.
